BIRD FEEDER AND FEED CARTRIDGE

George G. Hume, 3405 Rodman St. NW,
Washington, D.C.

Filed July 16, 1962, Ser. No. 70,933

Term of patent 14 years

(Cl. D31—2)

FIG. 1 is a perspective view of a bird feeder and feed cartridge, looking onto one side, showing my new design thereof; and

FIG. 2 is a perspective view looking onto the opposite side thereof.

The stippled portions of the drawing represent the feed cartridge of the feeder.

The dominant features of my new design reside in the portions thereof shown in full lines, the broken line showing of the tree branch being for illustrative purposes only.

I claim:

The ornamental design for a bird feeder and feed cartridge, substantially as shown and described.
